UNITED STATES PATENT OFFICE.

AMBROSE BERRY, OF GUNTERSVILLE, ALABAMA.

WIRE-FASTENER.

1,103,932.

Specification of Letters Patent.

Patented July 21, 1914.

Application filed May 11, 1914. Serial No. 837,915.

To all whom it may concern:

Be it known that I, AMBROSE BERRY, a citizen of the United States, residing at Guntersville, in the county of Marshall and State of Alabama, have invented certain new and useful Improvements in Wire-Fasteners, of which the following is a specification, reference being had to the accompanying drawings.

10 This invention relates to wire fasteners, and particularly to fasteners for fence posts, and has for its object the provision of a fastener of this character which may be readily connected with any standard form of post 15 and provided with adjustable clamping elements which are adapted to be placed at the requisite points in the length of the post according to the positions that the line wires are to occupy.

20 Another object of the invention is the provision of a fastener including an attaching plate secured to the post and constructed so as to permit the wire clamping elements to be removed from the plate expeditiously, 25 while further constructed with a view to effecting a substantial purchase of the elements against the wire under normal conditions.

Figure 1 is a front view of a post showing 30 the application of the wire clamp or fastener thereto; Fig. 2 is a vertical section through a portion of the post showing one of the clamping elements and illustrating the manner of confining the wire to the post 35 by means of said elements; Fig. 3 is a horizontal section taken on the line 3—3 of Fig. 1; Fig. 4 is a view similar to Fig. 3 showing a slightly modified form of the invention; and Fig. 5 is a similar view showing a still 40 further modified form of the device.

While I wish it to be understood that I do not desire, through the illustrations of the drawings, to limit myself to the precise manner of connecting the device to the post, it is 45 preferred, where an ordinary wooden post such as the one shown at A is employed, to construct the fastener so that it will properly accommodate the requisite number of line wires, and it is now described that the fastener 50 consists of a main attaching plate 1 having a uniform thickness throughout and being of a width whereby the edges of the plate come flush with the adjacent sides of the post. The plate is split along a longitudinal line and along transverse lines and 55 within the area defined by the margin of the

said split portions, the metal is upstruck so as to form a pair of flanges 2—2 spaced from each other along their inner longitudinal edges so as to form a continuous guide passage 3 for a purpose to be hereinafter described. The mentioned upstruck portions of the flanges 2—2 are preferably formed with relatively horizontal branches 4 that are designed to form the co-operative clamp- 60 65 ing parts of the device.

According to the number of line wires that go to constitute a part of the fence fabric, there are a corresponding number of clamping elements in the form of identical plates 70 5 which are arranged outwardly of the flanges 2—2 of the attaching plate 1. The plates 5 are identical with one another and each is upstruck respectively, at its upper and lower edges, so as to form the substantially concavo-convex gripping extensions 6 which extend in the direction of the horizontal surfaces 3 of the flanges 2. The said gripping surfaces or extensions 6 are serrated as at 7 and, as illustrated, the surfaces 80 6 traverse the vertical opening or passage between the flanges 2—2, and the serrated surfaces of the extensions 6 are designed to obtain an effective purchase with the horizontal extensions 3 at the time of the clamp- 85 ing of the wire upon the post.

Each of the plates 5 is provided with a central perforation 8 which receives a bolt 9 whose head has a width exceeding the distance between the vertical inner edges of the flanges 2 so that the projecting portions of the head will extend against the adjacent surfaces of the said flanges. In this manner, the bolt will be held against drawing outwardly of the guide slot as defined by the spacing of the flanges 2—2 from each other. The bolt carries an adjusting nut 10 which may be operated so as to cause the plate 5 to advance in the direction of the flanges 2. After one has positioned the plate 5 at the required point in the length of the attaching plate 1, the line wire B is placed beneath one of the concavo-convex extensions 6 and the clamping nut 10 is then adjusted so as to cause the plate 5 to be properly drawn into 100 105 clamping contact with the wire. On the final clamping of the plate 5 against the wire, the serrated surface of the extension 6 is drawn into contact with the adjacent surfaces of the flanges 2 so as to maximize the 110 gripping action of the plate 5 against the attaching plate 1 of the structure. The plate

5 is of a form whereby either one of the extensions 6 thereof may be employed as the active line wire receiving portion of the plate or, if desired, two line wires may be arranged in parallel relation and respectively associated with the companion extension 6 at the upper and lower edges of the plate. The attaching plate 1 of the structure is secured to the post A by passing bolts 11 through 10 the plate and through the post, as illustrated.

In the form of the invention shown in Fig. 4, the attaching plate 12 is secured to a post C by means of clips 13. These clips 15 are substantially of U-form and the branches 14—14 of the clips are connected by a curved branch 15, the latter being designed to embrace the corresponding back surface of the post C. Aside from the mode of connecting 20 the plate 12 with the post C, this form of the invention is identical with the form described in the first embodiment.

With reference to Fig. 5, a plate 16 is shown to have connected therewith clips 17 25 which are similar to the clips 13, above mentioned. The clip 17 is provided with right angularly extending branches that are adapted to accommodate themselves to the corresponding angularly disposed surfaces of a 30 post 18. In other words, the post 18 is of a rectangular configuration in horizontal section and the clip 17 is made to merely accommodate itself to such a form of post.

In either one of the devices mentioned, the 35 clamping plates 5 are adapted to be adjusted to any point in the length of the attaching plate and as the flanges 2—2 of the plate are upstruck by respectively slitting the metal on longitudinal and transverse 40 lines, it is evident that the ends of the flanges will be open so as to permit the heads of the fastening bolts to be freely passed into or out of engagement with the attaching plate, as may be desired.

Having thus fully described my invention, 45 what I desire to claim and secure by Letters Patent, is:—

1. A wire fastener for fence posts, comprising, an attaching plate secured to the post and provided with longitudinally extending flanges upstruck from the plate and disposed relative to each other so as to define between the flanges an intervening continuous slot, the ends of the slot being open, the said flanges having portions lying parallel to the adjacent surface of the post, and line wire clamping elements freely adjustable in the slot defined by the upstruck flanges of the plate and adjustable with relation to the flanges and serving to permit the line wire to be interposed between the flanges and the plate, the said plate having a serrated surface extending at right angles to the length of the slot between the flanges of the attaching plate and engaging the flanges of the attaching plate, as and for the purpose specified.

2. A line wire fastener for fence posts, comprising, an attaching plate secured to the post along one of the vertical surfaces 70 thereof, the said plate being respectively split on longitudinal and transverse lines and upstruck within the area defined by said transverse and longitudinal splits to form a pair of continuous flanges each having a terminal portion lying in parallel relation to the post, and a clamping plate freely adjustable over the flanges in the length thereof to secure the line wire between the flanges and the clamping plate, as 75 and for the purpose set forth.

In testimony whereof I hereunto affix my signature in the presence of two witnesses.

AMBROSE BERRY.
